UNITED STATES PATENT OFFICE.

JAMES F. BAKER, OF TROY, NEW YORK, ASSIGNOR TO CLUETT, PEABODY & CO., INC.,
OF TROY, NEW YORK, A CORPORATION OF NEW YORK.

PLAIT DISTRIBUTOR.

Application filed December 22, 1921. Serial No. 524,135.

To all whom it may concern:

Be it known that I, JAMES F. BAKER, a citizen of the United States, and resident of Troy, in the county of Rensselaer and State 5 of New York, have invented new and useful Improvements in Plait Distributors, of which the following is a specification.

This invention has to do with the folding of collars, cuffs and other articles in the 10 process of manufacture and more particularly to the folding of the margins of salient portions of articles such as the rounded corners or ends of collars and cuffs where the folded material tends to bunch and fold unevenly and therefore produce an irregular outline at the folded edge. For example, in 15 folding the margins of certain collar blanks having ends sharply rounded the plaits necessarily formed in the fold at the ends tend to distribute themselves irregularly and therefore produce a fold having uneven thickness, making it difficult to stitch, and also having an uneven edge, making it unsightly.

20 Objects of the present invention are to fold salient margins uniformly and smoothly, to avoid uneven edges at such folds, to facilitate the stitching of such folds, and to accomplish these results rapidly and without 25 injury to the fabric or other material being folded.

The invention involves flexing the margin of the salient portion into a series of waves extending along the edge thereof and then 30 folding the margin so that the waves produce plaits extending inwardly from the folded edge. The waves are preferably formed with an irregular edge so as to have a predetermined recurrence corresponding to 35 that of the plaits to be formed, ordinarily a regular recurrence.

The invention also comprises folding apparatus having a bed, which may be of any 40 usual or suitable type applicable to folding machines, also having a reentrant folding plate movable along the surface of the bed, and having a die arranged to press the article on the bed with the margin of the article overlying the plate, the folding plate 45 being movable over the die to fold the overlying margin, and the plate being provided with recesses or notches along its reentrant edge to plait the fold of the salient portion. The aforesaid notches are preferably formed

in a plait distributor which may be in the 55 form of a separate part adjustably mounted on the folded plate, and when so formed the teeth of the distributor defined by the aforesaid notches preferably extend only substantially to the edge of the folding plate. By 60 forming the notches in a distributor overlying the folding plate the folding edge of the plate may have a regular edge, in contradistinction to the irregular edge of the notched or serrated distributor, thereby facilitating 65 the smooth folding of the plaits without any tendency for the material to wedge or bunch in the notches.

In order to illustrate the nature of the invention more clearly one concrete embodiment is shown in the accompanying drawings 70 in which:—

Fig. 1 is a top plan view of a folding machine with the folding bars retracted;

Fig. 2 is a similar view with the folding 75 bars advanced into folding position and with the die head omitted;

Fig. 3 is an end view of the machine;

Fig. 4 is an enlarged top plan view of a 80 part of one of the folding plates showing the plait distributor mounted thereon; and

Fig. 5 is a section on line 5—5 of Fig. 4.

The machine chosen for the purpose of illustrating one application of the present invention in folding machines is similar to 85 that disclosed in the prior pending application Serial No. 509,383, filed October 21, 1921, and comprises a frame 1, four folding bars 2, actuating arms 3 fastened to the folding bars, shafts 4 eccentrically connected to 90 the arms 3 for actuating the folding bars, folding strips 5 fast on the under side of the folding bars 2, and a die head 6 swinging on pivot 7 for pressing the article to be folded against the bed plate 8 with the margins of 95 the article overlying the folding strips 5, the folding strips sliding over the die 9 to fold the margins thereover.

Inasmuch as the present invention is particularly applicable to the folding of corners 100 or ends having salient members which are relatively acute, I have shown the folding strips 5 as being adapted to the folding of the margins of a collar blank having the general outline of the die 9 as shown in Fig. 1, 105 this particular blank having pointed ends of relatively sharp curvature.

The particular application of the present

invention illustrated in the figures is in the form of a plait distributor 10 mounted on each of two of the folder strips 5 by means of a screw 11. The plait distributors have 5 V-shaped portions 12 conforming to the contour of those portions of the folding strips 5 which fold the pointed ends of the blank. The inner edge of the portion 12 is notched or serrated to provide V-shaped recesses into 10 which the margin of the blank is pressed when the die head is lowered. The points of the serrations preferably extend approximately to the inner edge of the folding strip 5.

15 In operation the blank is placed on the bed plate with its margins overlying the folding strips 5. The die head 6 is then lowered to press the central portion of the blank against the bed plate, the die 9 passing below 20 the level of the folding strips 5, the folding bars are then advanced from the position shown in Fig. 1 to the position shown in Fig. 2 whereupon the folding strips 5 slide over the die 9 and fold the margins of the 25 blank inwardly. Ordinarily the bed plate which is heated is then pressed upwardly and held for a brief interval to set the fold.

By virtue of the serrations or notches at 30 the pointed ends of the blank the margins of the ends are flexed into a series of waves extending along the margin when the die head is lowered and as the folding strips slide inwardly over the die 9 the ends of the blank are folded over with plaits corresponding to the waves formed by the 35 aforesaid recesses or notches, these plaits extending inwardly from the margins of the blank being uniformly distributed in accordance with the distribution of the 40 notches. In this way the ends are folded smoothly, the fullness being uniformly taken up by the plaits and the ends of the resulting folded blank being smooth and free from the irregularities resulting from folding machines heretofore employed.

45 I claim:

1. The method of folding an article having a salient portion which comprises flexing the margin of the salient portion into 50 series of waves extending along the meeting edges respectively of said salient portion, and then folding the margin so that the waves produce plaits extending at determinate points inwardly from the folded 55 edge.

2. The method of folding an article having a salient portion which comprises flexing the margin of the salient portion to form a series of substantially like waves at 60 determinate points spaced along said margin, and pressing the margin over to fold the margin with plaits corresponding to the several waves previously formed.

65 3. Apparatus for folding an article having a salient portion, comprising a bed,

reentrant folding plate movable along the surface of said bed, a die arranged to press the article on said bed with the margin of the article overlying said plate, the folding plate being movable over the die to fold 70 said margin, and means moving with the plate and providing a series of notches along the reentrant edge of the plate operating simultaneously on the article to plait the fold at said salient portion. 75

4. Apparatus for folding an article having a salient portion, comprising a bed, a reentrant folding plate movable along the surface of the bed, a die arranged to press the article on the bed with the margin of 80 the article overlying said plate, the folding plate being movable over the die to fold said margin, and a plait distributor having a series of like features constructed and arranged to form the material at said salient portion into a series of waves engageable by the folding plate to form uniform plaits extending along each side of the article at the salient portion thereof. 85

5. Apparatus for folding an article having a salient portion comprising a bed, a reentrant folding plate movable along the surface of said bed, said plate having a smooth and regular edge, a die arranged to press the article on said bed with 90 the margin of the article overlying said plate, the folding plate being movable over the die to fold said margin, and a plait distributor overlying the folding edge of said plate to distribute the plaits in the fold 95 of said salient portion.

6. Apparatus for folding an article having a salient portion comprising a bed, a reentrant folding plate movable along the surface of said bed, a die arranged to press 105 the article on said bed with the margin of the article overlying said plate, the folding plate being movable over the die to fold said margin and a plait distributor having teeth extending substantially to the folding edge of said plate along its reentrant portion to distribute the plaits in the fold 110 of said salient portion.

7. Apparatus for folding an article having a salient portion comprising a bed, a 115 reentrant folding plate movable along the surface of said bed, a die arranged to press the article on said bed with the margin of the article overlying said plate, the folding plate being movable over the die to 120 fold said margin, and a plait distributor fast to said plate, the distributor having a serrated edge extending along the reentrant edge of the folding plate to distribute the plaits in the fold of said salient portion. 125

8. Apparatus for folding an article having a salient portion comprising a bed, a folding plate movable along the surface of said bed, a die arranged to press the article on said bed with the margin of the article 130

overlying said plate, the folding plate being movable over the die to fold said margin and having a reentrant portion corresponding to said salient portion, and a plait distributor overlying said reentrant portion, the edge of the reentrant portion being regular and the edge of the plait distributor being irregular.

9. An infolder for folding machines comprising a folding plate having a reentrant portion and means providing series of recesses distributed along the respective margins of the meeting edges of said reentrant portion.
10. An infolder for folding machines comprising a folding plate having a reentrant portion and a plait distributor on said plate having a series of V-shaped re-
- 15.

cesses distributed along the margin of said reentrant portion.

11. An infolder for folding machines comprising a folding plate having a reentrant portion and a plait distributor overlying the margin of said reentrant portion with notches along the edge thereof.

20

12. An infolder for folding machines comprising a folding plate having a reentrant portion and a plait distributor overlying said plate, the distributor having teeth extending substantially to the folding edge of said plate along the reentrant portion of the plate.

25

Signed by me at Troy, New York, this 16 day of December, 1921.

JAMES F. BAKER.
